UNITED STATES PATENT OFFICE

168,301

OVERSHOE

Theodore W. Hayward, North Platte, Nebr., assignor to Stoneward, Inc., North Platte, Nebr., a corporation of Nebraska

Application July 23, 1952, Serial No. 20,734

Term of patent 14 years

(Cl. D7—4)

To all whom it may concern:

Be it known that I, Theodore W. Hayward, a citizen of the United States and a resident of North Platte, in the county of Lincoln, State of Nebraska, have invented a new, original, and ornamental Design for an Overshoe, of which the following is a specification, reference being had to the accompanying drawing, form a part thereof.

Fig. 1 is a rear perspective view of an overshoe embodying my new design; and

Fig. 2 is a front perspective view of the same.

The opposite side of the overshoe from that illustrated in the figures is substantially the same in appearance as the side shown.

I claim:

The ornamental design for an overshoe, as shown and described.

THEODORE W. HAYWARD.
